UNITED STATES PATENT OFFICE.

BERNHARDT F. P. VEDDER, OF MILWAUKEE, WISCONSIN.

REEL FOR ELECTRIC IRONS.

Application filed November 11, 1926. Serial No. 147,688.

This invention relates to a reel for an electric iron.

In using electric irons, difficulty has been experienced due to the trailing of the cord over the ironed material and otherwise interfering with the free use of the iron. Various attempts have been made to overcome this defect by the use of reels, but these attempts have not proven wholly satisfactory as the device required a modification of the standard type of iron so as to adapt it to the use of the reel.

This invention is designed to overcome the defects noted above and objects of such invention are to provide a novel form of attachment in which a reel is provided on which the electric cord is wound, and in which the device is so constructed that it cooperates with the standard type of electric iron in a novel manner utilizing primarily the terminals carried by the standard iron for supporting the device and providing means for preventing the inadvertent withdrawal of the device from the terminals.

Further objects are to provide a simple, easily produced attachment which may be very readily applied to a standard iron without modifying the construction of the iron, such device utilizing parts of the iron for locking it in place upon the terminal connectors of the iron.

Further objects are to provide a device of the above nature in which the spring rewound reel may be held against rewinding when the desired amount of cord has been withdrawn from the reel, and to provide means of the nature of a ratchet which may be rendered inoperative when desired, for example, when it is desired to rewind the cord. In this manner, it is possible with this invention to withdraw the requisite amount of cord for the particular work in hand and thus have the exact length needed while permitting additional amounts to be withdrawn.

Further objects are to provide an eminently practical and serviceable type of device which is not heavy nor extremely bulky and which does not interfere with the free use of the iron.

An embodiment of the invention is shown in the accompanying drawings in which:

Figure 1 is a vertical sectional view centrally through the device;

Figure 2 is a sectional view on the line 2—2 of Figure 1;

Figure 3 is a sectional view on the line 3—3 of Figure 1;

Figure 4 is a detail of the terminal receiving portion of the device;

Figure 5 is a view showing the device in place upon an iron, and showing a part of the iron in section.

Referring to the drawings, it will be seen that the attachment comprises a casing 1 which is preferably formed of stamped metal. This casing has a cylindrical outer portion provided with an outwardly recessed part 2 immediately adjacent the peripheral portion of the reel 3. This reel is carried by suitable ball bearings 4 mounted upon a transverse pin or bolt 5 which extends completely through the device. Preferably, the reel is formed of an insulating material and has a hub portion 6 which carries a pair of rings 7, suitable brushes or fingers 8 being carried by an insulating block 9 mounted within the casing and bearing upon the insulating ring.

An electric cord 10 (see Figure 5) is wound upon the reel and extends outwardly through a cut-away portion of the projecting rib 2 of the casing 1. The projecting portion allows additional room for the winding of the cord. The terminals of the cord are connected to the brushes 8, as indicated in Figure 2, and the other end of the cord is attached to a plug 11 in the usual manner. The brushes are connected electrically to the terminal receiving portions or metal members 12 carried within a two-part insulating block 13, such block being secured to the casing in any suitable manner, preferably as indicated in Figure 1. This insulating block 13 projects downwardly and forwardly at an angle and the terminals of the iron which project upwardly and rearwardly at an angle in the standard types of irons are received within the members 12. The insulating block is carried by an outwardly projecting arm 14 of a metal strip which is rigidly secured to the casing. This metal strip has an outwardly projecting apertured ear 15 which is held to the handle of the iron by means of the standard elongated bolt 16 which attaches the handle to the other portions of the iron, as indicated in Figure 5. In applying the device, it is merely necessary to remove the nut 17 of the bolt 16, slip the block 13 over the terminals of the iron and the ear 15, and over the end of the bolt 16. Thereafter the nut

17 is replaced and serves to lock the device upon the terminals so that the device is very securely supported without altering the construction of the iron in any manner.

5 The spring mechanism for rewinding the reel consists of a spring drum or casing 18 (see Figure 2) of standard construction. The rotary portion of this spring motor carries a large gear 19 which meshes with a pinion 20 rigid with the reel. Thus, a relatively long extension of the cord may be had without unduly stressing the spring.

One face of the reel 3, as may be seen from Figures 1 and 2, is provided with 15 ratchet teeth 21 which may be engaged by the spring arm or leaf spring 22 carried within the casing 1. This spring arm is controlled by a thumb nut 23 which is secured loosely to the spring at its free end. The 20 thumb nut projects outwardly through an aperture 24 formed in the casing and is provided with a flattened portion or shank, as indicated at 25. This aperture 24 is in reality a slot so that when the flattened portion 25 is turned longitudinally of the slot, the stem of the thumb nut or thumb piece 23 is free to drop inwardly under the influence of the spring 22 and, consequently, the spring acts as a pawl for the ratchet teeth 21. 25 However, when it is desired to render the pawl and ratchet mechanism inoperative, it is merely necessary to raise the thumb piece 23 and give it a quarter turn. This causes the flattened portion 25 to rest crosswise of the slot and consequently hold the thumb piece and spring retracted.

30 In using the device, it is applied to the iron as previously described, and is securely locked in place upon the iron without altering the construction of the iron. A certain length of cord is pulled outwardly from the reel sufficient for the particular work in hand and the pawl and ratchet mechanism is rendered operative, thus locking the cord against retraction. If additional amounts 40 are required the pawl and ratchet mechanism permit the free unwinding of the cord, but prevents its rewinding. However, when 45 it is desired to rewind the cord it is merely necessary to manipulate the thumb piece 23, as previously described.

50 In certain types of irons the handle is held to the uprights by means of screws or other fastening means. In this case, the attachment carried by the terminals is held in place 55 against slipping from the terminals by means of the screw or other securing means at the rear of the handle.

It will be seen that a very simple and 60 serviceable type of spring ring has been provided which may be attached to standard

electric irons with the minimum of effort. Further, it will be seen that the device does not interfere with the free use of the iron, and yet maintains the correct length of cord 65 as desired.

It will be seen further that the device operates very freely and does not in any way hamper the operator.

70 Although the invention has been described in considerable detail, such description is intended as illustrative rather than limiting as the invention may be variously embodied and as the scope of such invention is to be determined as claimed.

75 I claim:

1. An attachment for an electric device provided with terminals carried by said terminals, means for retaining said attachment in place and preventing its slipping from said terminals, a reel carried by said attachment, an electric cord wound upon said reel and connected to said terminals, and means for locking said reel against rotation.

80 2. An attachment for an electric device provided with terminals secured to said device and connected to said terminals, a reel carried by said attachment, an electric cord wound upon said reel and connected to said terminals, a spring tending to rewind said reel, and means for temporarily preventing the rewinding of said reel.

85 3. An attachment for an electric device provided with terminals carried by said terminals and having a reel, an electric cord wound upon said reel, a spring tending to rewind said cord, said reel having a ratchet wheel, a pawl adapted to be thrown into and out of operative position for preventing rewinding of the cord, and a thumb nut carried by said spring and adapted to lock said spring out of engagement with said ratchet wheel when said nut occupies one position of adjustment.

90 4. The combination of an electric iron provided with a pair of projecting terminals and having a pair of uprights, a handle positioned between said uprights, and securing means holding said handle to said uprights, an attachment supported by said terminals and having a reel, said attachment being locked in place against slipping from said terminals by means of said securing means, an electric cord wound upon said reel and connected to said terminals, and means 95 for rewinding said reel.

100 In testimony that I claim the foregoing I have hereunto set my hand at Milwaukee, in the county of Milwaukee and State of Wisconsin.

105 BERNHARDT F. P. VEDDER.
